US0D1074436S

(12) **United States Design Patent** (10) **Patent No.:** **US D1,074,436 S**
McCandless et al. (45) **Date of Patent:** ** *May 13, 2025

(54) **INSERT WITH BASE, LID, AND CARTRIDGES**

(71) Applicant: **Altria Client Services LLC**,
 Richmond, VA (US)

(72) Inventors: **Todd M. McCandless**, Richmond, VA (US); **Brian M. Casey**, Richmond, VA (US); **Christopher L. Simpson**, Richmond, VA (US)

(73) Assignee: **Altria Client Services LLC**,
 Richmond, VA (US)

(*) Notice: This patent is subject to a terminal disclaimer.

(**) Term: **15 Years**

(21) Appl. No.: **29/853,746**

(22) Filed: **Sep. 19, 2022**

(51) LOC (15) Cl. **09-03**

(52) U.S. Cl. **USPC D9/759**

(58) **Field of Classification Search**

USPC D3/202, 203.1, 203.2, 203.3, 272, 273, D3/274, 283, 304, 318, 319; D7/737, D7/738, 739, 740, 741, 744, 751, 755, D7/756, 759, 600.1, 624.1, 387, 388; D9/737, 738, 739, 740, 741, 744, 751, D9/755, 756, 759, 414, 418, 424, 430, D9/431, 432, 433, 500, 501, 502, 503

CPC B65D 75/327; B65D 5/2057; B65D 5/307; B65D 2575/3227
